SAFETY RAZOR

Louis Nagy, Detroit, Mich., assignor of one-half
to Stephen F. Halach, Detroit, Mich.

Application March 7, 1934, Serial No. 714,486

5 Claims. (Cl. 30—12)

This invention relates to a safety razor.

It is an object of the invention to provide a new and novel construction of razor in which the comb is of a dual type, associated with a double edged thick bodied blade, the comb and blade being readily tilted to vary the angle of the cutting edge of the blade.

It is a further object of the invention to provide means within the handle of the razor co-operable with the comb to vary the tilting action of the comb upon rotation of the handle.

It is a still further object of the invention to provide novel tilting means for a razor comb which embodies few parts of simple construction, 15 readily assembled, and which is liable in a minimum degree to derangement.

Additional objects, advantages and features of invention will be apparent from the following description considered in conjunction with the accompanying drawing; nevertheless, it is to be understood that the invention is not confined to the disclosures, being susceptible of such changes and modifications as define no material departure from the salient features of the invention as expressed in the appended claims.

In the drawing:

Figure 1 is a longitudinal sectional view of a razor constructed in accordance with my invention.

Figure 2 is a front elevation, partly in section.

Figure 3 is a longitudinal sectional view of a modification illustrated in Figure 1.

Figure 4 is a fragmentary front elevation of the razor, partly in section.

Figure 5 is a cross section on the line 5—5 of Figure 4.

Figure 6 is a cross section on the line 6—6 of Figure 3.

Figure 7 is a cross section on the line 7—7 of Figure 3.

Figure 8 is a cross section on the line 8—8 of Figure 3, and

Figure 9 is a plan view of the blade.

Heretofore, in the construction of razors, it has been the practice to provide blades of very thin steel which are flexed upon securing thereof to the comb of the razor, and while such razors are more or less satisfactory, the most efficient blade is one having a substantial body, since such blade may be properly tempered to maintain a proper cutting edge. Obviously, a thick blade cannot be flexed to obtain the necessary angle to effect a smooth, clean shave, and I have therefore devised a unique blade holder which is adjustable to present the cutting edge at the most advantageous angle.

In carrying out my invention I provide a head 10 including the usual construction of dual combs 11. The head 10 has a pair of ears 12 at opposite ends thereof to which arms 13 of a yoke 14 are

pivottally connected by pintles 15 and a handle 16 is formed as an integral part of the yoke. It will thus be seen that the head 10 is swingingly connected with the handle.

The head 10 further includes a pair of lugs 17 projecting from the outer face of the head 10 and comprise extension portions 18 lying parallel with the body 10 and spaced therefrom a distance slightly greater than the combined thickness of a blade 19 and retainer plate 20, for a purpose now 10 to be explained.

The blade 19 is formed of heavy, tempered steel, having cutting edges 19' and a pair of slots 21 extend longitudinally thereof adapted to receive respective lugs 17 therethrough, and the retainer plate 20 is similarly slotted as indicated at 22. In assembling the blade and retainer plate upon the head, the slots 21 and 22 of the blade and retainer plate are aligned and presented over the lugs 17 and then given an edgewise sliding movement in 20 the direction of the lugs so that the extensions 18 will engage over a portion of the retainer plate 20. In order to more readily engage the plate 20 by the lugs 17 the underside of the extensions 18 may have a slight taper, as indicated at 23. From 25 the foregoing, it will be readily seen that the blade 19 will be securely held upon the comb head 10.

The construction of head and blade securing means above described is embodied in both forms of the invention herein disclosed, although other 30 means of securing the blade to the head may be employed.

Attention is now invited particularly to Figures 1 and 2 of the drawing wherein I have illustrated means for tilting and securing the head 10 to one 35 side or to the other of the handle 16. The handle 16 is shown as of tubular formation of the required length and adjacent the outer end thereof the interior diameter of the tube is reduced as at 24, forming an annular seat 25. A tubular 40 shaft 26 is slidably and revolvably disposed within the handle 16, and is reduced in diameter as indicated at 27, to fit within the bore 28 of the reduced portion 24. A helical spring 29 is positioned upon the reduced portion of the shaft 26, 45 and bears upon the shoulder 30 and the annular seat 25.

The shaft 26 projects beyond the tubular handle 16 a short distance and upon the projecting portion of the shaft a sleeve 31 is secured thereto 50 by means of a screw 32, extended into impinging contact with the shaft 26. The sleeve 31 has a bore 33 of a diameter to freely receive the end portion of the handle 16 therewithin, as clearly shown in Figure 1.

The shaft 26 is of a length to contact the head 10, and in order to cause a tilting movement of the head, the shaft 26 terminates a cam member 34 in abutting relation with the head. The cam 34 is shown as formed as an integral part 60

of the shaft 26 and includes lateral extensions 35 and 36 terminating in cam faces 37. The cam faces are arranged at an angle with respect to the shaft 26, and it will therefore be apparent 5 that upon rotation of the shaft by means of the sleeve 31, the cam 34 as an entirety will be rotated, and since the head 10 is in abutting relation with the cam the head will be caused to swing on the pivots 15. Thus the head 10 will 10 be tilted to an angle corresponding to the position and inclination of the surfaces of the cams, and a complete rotation of the shaft 26 will cause the head 10 to assume an inclination opposite to that shown in Figure 1.

15 For the purpose of enabling cleaning of the razor after use, the shaft 26 is retracted by an outward pull upon the sleeve 31, compressing the spring 29, and by a slight rotation of the shaft 26 one of the cam faces 37 may be seated upon 20 one of the lugs 38 formed upon the inner faces of the yoke 14. Thus the cam 34 will be securely held against contacting engagement with the head 10, so that cleaning of the razor will be permitted. With release of the cam from engagement 25 with the lug 38 the spring 29 will force the shaft 26 outwardly again to position the cam in engagement with the head 10.

In Figures 3 to 8 a modification of the invention is illustrated, and in this form, the head 10 is pivoted to the arms of the yoke as previously described, but the handle 16' is shown as a tube of the same diameter throughout its length but at the base of the yoke arms 14 and extending across the bore 39 of the handle, there is a spacer bar 40. This bar 40 is shown as a separate member from the handle, but preferably is securely seated and may be soldered, as at 41' in the base of the yoke. The bar 40 divides the bore 39 into two semi-circular passage-ways, and in each of 35 the passage-ways there is longitudinally slidably shaft members 42 and 43. The shafts 42-43 have a semi-circular formation corresponding to the bore 39 and a plane straight face 44 contacting the sides of the bar 40. It will be apparent 40 that the bar 40 prevents rotation of the shafts 42-43 but free longitudinal movements will be permitted, as will be presently explained.

The shaft 42 is slightly less in length than the shaft 43, and at a point approximately midway 50 of the shaft 42 there is formed a series of left-handed screw threads 45 and the shaft 43 is provided with screw threads 46 having right handed pitch, these threads occurring upon the shaft 55 at the lower extremity thereof and extending a substantial distance inwardly thereof. The shafts 42-43, where the screw threads occur, have a semicircular formation and when arranged in opposed relation define a bore having threads of opposite pitch. Within the bore thus 60 defined by the shafts 42-43 there is arranged a shaft 47, this shaft having screw threaded portions 48 and 49 corresponding to respective threads 45 and 46.

The shaft 47 extends beyond the handle 16' 65 and has fixed thereto by a set screw 50 an operating knob 51. The knob includes a reduced portion 52 seated within the bore of the handle 16'. An annular groove 53 is formed in the reduced portion 52 and receives a screw 54. The screw 54 may have a rounded end whereby free rotation of the shaft 47 will be permitted yet retaining the knob against withdrawal.

The ends of the shafts 42-43 adjacent the

head terminate in oppositely disposed wing members 55, each of which is provided with cam members 56 extending at right angles thereto and in contacting relation with the back wall 5 of the head 10.

In adjusting the inclination of the head 10, rotation of the shaft 47 by the knob 51 in a right hand direction, the shaft 43 will be moved outwardly in the direction of the head 10 causing the cam associated therewith to engage the head, 10 tilting the same to the degree desired. Rotation of the shaft 47 in a left hand direction will retract the shaft 43 and move the shaft 42 outwardly so as to engage and tilt the head 10 to the angle 15 desired.

In both forms of the invention it will be possible to vary the inclination of the head 10 by rotation of the knob members 31 or 51, and it will be noted that the cutting edges 19' may be properly set to secure the most efficient cutting angle, 20 without the need for flexing of the blade.

I claim:—

1. A razor comprising a head member having parallel projecting ears, a tubular handle member having arms pivotally connected with the ears, 25 a revoluble shaft journaled within the handle member, a cam carried by the shaft and in contacting relation with the head, spring means urging said cam into engagement with the head, and a sleeve revolvably supported by the handle 30 and keyed to said shaft.

2. A razor comprising a head member having parallel projecting ears, a yoke member having an arm pivotally connected to respective ears, lug members on the yoke, a tubular handle fixed to 35 said yoke, a revoluble shaft journaled within the handle, a cam carried by the shaft and normally in contacting relation with the head, spring means urging the cam into engagement with the head, a sleeve revolvably supported by the handle 40 and keyed to said shaft, said shaft being retractable against the tension of the spring and rotatable to position the cam behind one of the lug members.

3. A razor comprising a head member, having 45 parallel projecting ears, a yoke member having an arm pivotally connected to respective ears, a tubular handle fixed to said yoke, a pair of shafts slidably supported within said handle, the shafts having concave portions, screw threads formed in 50 the concave portions, the threads of one shaft having a pitch opposite to that of the other shaft, a shaft revolvably supported within the handle and having threaded portions corresponding to the threads of the first two named shafts, and 55 said first two named shafts having cam members in bearing contact with said head, and means for rotating the revolvable shaft.

4. A razor comprising a swingable head member, a handle connected therewith, an angular 60 cam member revolvably supported by the handle, said cam member having contact relation with the head, and means for revolving the cam member whereby to tilt and hold the head at various angles of inclination.

5. A razor comprising a swingable head member, a tubular handle pivotally connected thereto, a shaft revolvably supported in the handle, means carried by the handle for moving the shaft, said shaft having an angular cam face in contacting 70 relation with the head whereby to tilt the head to various inclinations upon movement of the shaft.
